(57) **CLAIM**

The ornamental design for a biological information sensor, as shown and described.

DESCRIPTION

FIG. 1 is a top perspective view of a biological information sensor showing our new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1; and,

FIG. 10 is an enlarged view of portion 10 in FIG. 2.

The broken lines in the drawings show portions of the biological information sensor that form no part of the claimed design. The dash-dot-dash broken lines define the bounds of the enlargements and form no part of the claimed design.
